UNITED STATES PATENT OFFICE.

FRANCESCO CIRELLI, OF PHILADELPHIA, PENNSYLVANIA.

TIME-CONTROLLED STARTING MECHANISM.

1,345,584.

Specification of Letters Patent.

Patented July 6, 1920.

Application filed August 20, 1918. Serial No. 250,664.

To all whom it may concern:

Be it known that I, FRANCESCO CIRELLI, a subject of the King of Italy, residing at Philadelphia, in the county of Philadelphia and State of Pennsylvania, have invented 5 certain new and useful Improvements in Time-Controlled Starting Mechanism, of which the following is a specification.

One object of my invention is to provide 10 means for automatically starting sound reproducing machines at any predetermined time so that the sound reproduced can serve as an alarm, for example, instead of the ordinary alarm clock bell and in this manner 15 a person can be awakened with music from the machine instead of a noise such, for example, as by an alarm clock bell.

Another object is to include in my invention means which will permit a record placed on the machine to attain its proper 20 momentum or number of revolutions per minute before the sound transmitting means is brought into engagement therewith. In this manner the machine will start playing 25 at the proper and intended pitch of tone.

A further object is to so construct my invention that the record or any of the sound transmitting parts cannot be injured due to the automatic starting of the 30 machine.

Another object is to so construct my invention that the record will be automatically stopped after having been played.

These objects, and other advantageous 35 ends which will be described hereinafter, I attain in the following manner, reference being had to the accompanying drawings in which—

Figure 1 is a front elevation of a sound 40 reproducing machine equipped with my invention; certain of the parts being shown in section,

Fig. 2 is a top plan view of Fig. 1 on an enlarged scale and with the cover removed,

45 Figs. 3 and 4 are enlarged fragmentary plan views showing the position of certain of the parts during the operation of my invention,

Fig. 5 is a fragmentary sectional elevation 50 showing certain of the parts of my invention in a "set" position,

Fig. 6 is a top plan view of a member for 55 supporting the record needle out of engagement with the record when the parts are in a "set" position and movable to cause the

record-engaging needle to enter the initial playing groove of the record,

Fig. 7 is a top plan view of a member 60 adapted to form a pivotal support for the member shown in Fig. 6,

Fig. 8 is a side elevation of Fig. 7,

Fig. 9 is a perspective view of a housing in which the member of Figs. 7 and 8 slides,

Fig. 10 is a fragmentary sectional elevation 65 taken on the line 10—10 of Fig. 3, and

Fig. 11 is a sectional elevation taken on the line 11—11 of Fig. 10.

Referring to the drawings, 15 represents 70 a sound reproducing machine cabinet having a top board 16 which is mounted below the top edge 17 of the cabinet so as to provide a space 18 for a record-supporting turntable 19 which can be rotated by a motor 75 within the cabinet (not illustrated).

A tone arm 20 is mounted on the top board 16 and supports a sound box 21 having a needle holder 22 for the record-engaging needle 23, said tone arm being pivotally 80 mounted so as to swing in horizontal and vertical planes and so that the sound box has a similar movement.

The cabinet 15 has a chamber 24 below the top board 16 and this chamber is normally closed in the front by hinged doors 85 25. I mount within the chamber 24 an alarm clock 26 which may be of any construction which has a shaft 27 which rotates at a predetermined time due to the "setting" 90 of the clock.

I secure an arm 28 on the shaft 27 of the clock which, when the shaft rotates, is adapted to strike against a depending L-shape stem 29 on a bar 30. The bar 30 is 95 adapted to slide in bearings 31 mounted on the top board 16, and a slot 32 is provided in said top board to allow the stem 29 to depend into the chamber 24 and within the path of movement of the arm 28. It will 100 thus be understood that the arm 28 during its rotation will engage the stem 29 and slide the bar 30 in the direction of the arrow x, as shown in Fig. 2.

One end of the bar 30 is provided with 105 an anti-friction roller 33 which engages one edge of a lever 34. This lever 34 may be of any of the usual forms which are used on sound reproducing machines and which when moved causes the release of the turn- 110

table and permits the latter to be rotated by its motor. It will thus be understood that when the bar 30 is moved in the direction of the arrow α the lever 34 will be moved to start the rotation of the turntable 19.

I mount on the top board 16 a housing 35 so that said housing is fixed with relation to the top board. This housing includes a bridge 36 provided with a tapped hole 37 into which is adapted to fit a thumb screw 38.

A slidable member 39 has an extension 40 adapted to fit within the housing 35 and slide longitudinally therein. The thumb screw 38 serves to engage the slidable member 39 and thereby secure the same to the housing in various longitudinal positions.

A head 41 is provided on the member 39 and has a post 42 adapted to form the pivot for a support 43. This support 43 has a hole 44 which fits over the post 42, and a headed screw 45 is adapted to prevent raising movement of the support from the post 42.

The support 43 has an angularly disposed slot 46 into which fits an L-shape hooked end 47 of a link 48; the opposite end of said link being loosely fitted within a hole 49 in one end of a double ended lever 50 which is pivoted between its ends on a post 51 secured on the top board 16. The opposite end of the lever 50 is connected by a link 52 to the lever 34.

The support 43 has at its end opposite the slot 46 two projecting fingers 53 and 54 and a lip 55 so arranged that the finger 54 is located between the finger 53 and the lip 55, a detail of this construction being clearly shown in Fig. 6. Either of the fingers 53 or 54 is capable of supporting the needle holder 22, according to the size of the record, so that the needle 23 when the needle holder is so supported will be out of engagement with the record 56 upon the turntable 19. The parts are so arranged that the fingers 53 and 54 and lip 55 occupy a plane slightly above the edge of the record and turntable.

Considering that the needle holder 22 is resting upon the finger 54, as shown in full lines in Figs. 2, 3, and 5, and that the end 47 of the link 48 occupies a space between the ends of the slot 46: when the arm 28 of the alarm clock starts to rotate, it will engage the stem 29 and move the bar 30 longitudinally to cause the anti-friction roller 33 to move the lever 34 into a position to release the turntable 19 and permit it to rotate. This movement of the lever 34 will turn the double ended lever 50 on its pivot 51 through the medium of the link 52 and such movement of the lever 50 will cause a longitudinal movement of the link 48. However, this longitudinal movement of the link 48 cannot move the support 43 on its pivot until the end 47 of said latter

link engages the end of the slot 46. In other words, there is lost motion between the link 48 and the support 43 and during the time required to move the end 47 into engagement with the portion of the support 43 which forms the end of the slot 46, the turntable will attain its proper momentum or speed. Just as soon as the link end 47 engages the end of the slot 46 the support 43 will be turned on its pivot so that the finger 54 will be moved from under the needle support 22 and, due to the beveled upper surface 57 of said finger 54, the needle holder will slide therefrom and permit the needle to engage the upper surface 58 of the record 56, said portion being to the outside of the initial playing groove so that there is no possibility of injury to the record due to the lowering movement of the needle into engagement with the record.

The lip 55 is so arranged that after the needle 23 has engaged the portion 58 of the record, said lip 55 will push against the needle holder 22 to slide the needle 23 into engagement with the initial playing groove of the record. Thus the needle will gently engage the record and the initial playing groove thereof and since considerable time elapses between the initial movement of the starting lever 34 and the final pushing movement of the lip 55, the turntable will have ample time to attain the proper speed before the record starts playing.

I prefer that the machine be automatically stopped after having finished playing the record and I may employ any form of automatic stopping mechanism for this purpose. However, in the drawings I have illustrated an automatic stop 60, such as covered by my United States Patent 1,208,749, December 19, 1916, and I provide the tone arm 20 with a pin 61 or other projection adapted to engage and operate the stop 60 after the record has been played.

The position of the support 43 relative to the record can be changed by moving the slidable member 39 within the housing 35 to accommodate variations in the size of the record. Also, the finger 53 serves as an auxiliary finger which can be used to support the needle holder 22 in the same manner as above described in connection with the finger 54. For example, the auxiliary finger 53 could be employed when a record or machine of different diameter is used and between these two fingers 53 and 54 and the adjustment of the slidable member 39 my invention is applicable to records and machines of various types and sizes. It will be noted that when the finger 53 is used to support the needle holder, then the finger 54 will act to push the needle into the initial playing groove of the record in the same manner as above described in connec-

tion with the lip 55. It will be noted that when the finger 53 is employed to support the needle holder 22 as above mentioned that a link 48 of different length can be employed to permit the finger 53 to be swung inwardly toward the center of the turntable and the member 34 can be slid as above described to permit the proper adjustment of the parts so as to provide a dwell of the support 43 until the turntable has secured its proper speed.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

25 1. The combination of a record, means for moving said record; means movable to effect the movement of said record by said first means; sound transmitting means for engagement with said record; a support for holding said sound transmitting means out of engagement with said record; and time-controlled means initially operative to actuate said second means to start the record and afterward operative to move said support into a position to permit said sound transmitting means to engage said record; substantially as described.

2. The combination of a record, means for moving said record; means movable to effect the movement of said record by said first means; sound transmitting means for engagement with said record; a support for holding said sound transmitting means out of engagement with said record; and time-controlled means initially operative to actuate said second means to start the record and afterward operative to move said support into a position to permit said sound transmitting means to engage a non-reproducing portion of said record, said support having a portion movable by said time-controlled means for moving said sound transmitting means into engagement with a reproducing portion of said record; substantially as described.

3. The combination of a record, means for moving said record; means movable to effect the movement of said record by said first means; sound transmitting means for engagement with said record; a support for holding said sound transmitting means out of engagement with said record; time-controlled means initially operative for actuating said second mentioned means to start said record and afterward operative to move

said support into a position from under said sound transmitting means to permit the latter to engage a non-producing part of said record; and means operative by said time-controlled means for laterally moving said sound transmitting means into engagement with a sound reproducing portion of the record; substantially as described.

4. The combination of a record, sound transmitting means for engagement with said record; a movable support having a portion for holding said sound transmitting means out of engagement with said record; and automatically operative means for moving said support to cause said portion to be moved out of holding engagement with said sound transmitting means and thereby permit the latter to engage said record, said movable support having a portion operative to move said sound transmitting means into engagement with a reproducing portion of said record during a continued movement of said support by said automatically operative means; substantially as described.

5. The combination of a record, means for moving said record; means movable to effect the movement of said record; sound transmitting means for engagement with said record; a support for normally holding said sound transmitting means out of engagement with said record, said support having a slot therein; means operatively connected to said movable means and having a portion in engagement with said slot; and time-controlled means automatically operative to move said second means to effect the movement of said record, by said first means, and of said connecting means; said portion being freely movable through said slot until it engages the end thereof and then operative to actuate said support to move the latter out of holding engagement with said sound transmitting means to permit the latter to engage the record; substantially as described.

6. The combination of a record, means for moving said record; means movable to effect the movement of said record; sound transmitting means for engagement with said record; a support for normally holding said sound transmitting means out of engagement with said record, said support having a slot therein; means operatively connected to said second means and having a portion in engagement with said slot; and time-controlled means automatically operative to move said second means to effect the movement of said record, by said first means, and of said connecting means; said portion being freely movable through said slot until it engages the end thereof and then operative to actuate said support to move the latter out of holding engagement with said sound transmitting means to permit the latter to engage the record, said support hav-

ing a portion adapted to laterally move the sound transmitting means into engagement with a reproducing portion of said record after engagement of said sound transmitting means with the record; substantially as described.

In testimony whereof I have signed my

name to this specification in the presence of two subscribing witnesses.

FRANCESCO CIRELLI.
